LATCH MEANS FOR JAW WRENCHES

Walter Sniezyk, Detroit, Mich.

Application September 23, 1948, Serial No. 50,810

2 Claims. (Cl. 81—129)

1

My improvement pertains to a wrench which by reason of a movable member may be effectively applied to nuts of varying sizes within the limits of the capacity of the wrench.

The wrench is of a type having a stationary surface for application to the head of a nut from one side, and a sliding member by means of which the head may be clamped from the opposite side. Once this is done, the sliding member may be locked against displacement. The advantages of this particular type of wrench will become obvious in the course of the description of my wrench with reference to the accompanying drawings in which:

Fig. 1, is a perspective view of the wrench;

Fig. 2, is a plan elevational view of said wrench;

Fig. 3, is a bottom view of the wrench with parts shown in section;

Fig. 4, is a longitudinal sectional view of line 4—4 of Fig. 2;

Fig. 5, is a perspective view of a sliding member of my wrench;

Fig. 6, is a sectional view on line 6—6 of Fig. 4;

Fig. 7, is a sectional view on line 7—7 of Fig. 4;

Fig. 8, is a sectional view on line 8—8 of Fig. 4;

Fig. 9, is a fragment of my wrench in section, showing a detail of construction therein;

Fig. 10, is a sectional view on line 10—10 of Fig. 9;

Similar numerals refer to similar parts throughout the several views.

The wrench includes a solid oblong member 10 of uniform thickness and gradually tapering sides from head 11 towards the handle portion 12. The mid-portion of said member is open as shown at 13 from a line adjoining the tapered end to a line adjoining the head, said opening being of uniform width throughout. In other words, the member may be described as an oblong frame with side rails thickening from the handle portion gradually toward the head 11. The inner surfaces 14 of the opening are set at right angles to the top surface of the wrench as best shown in Fig. 1, each of the side surfaces 14 being grooved longitudinally as shown at 15. A portion of each side rail in the handle part of the wrench is cut out on the underside of the wrench as shown at 16. This is done for the purpose of inserting into the frame a sliding member which will be described presently.

Each side surface 14 is provided with a plurality of aligned apertures, some of which, marked 17, are located above the level of the groove 15, and some of which, marked 17a, are located below the level of said groove. The apertures at

2

each level, are spaced from each other and marked as shown at 32 by numerals arranged in sequence, increasing in value in the direction of the handle.

Disposed within the opening 13 is a sliding member generally indicated by numeral 18. The member best illustrated in Fig. 5, includes a thick body 19 having at each side a horizontal fin or tongue 20 fitting into a respective groove 15 for a sliding movement therein. Set in a transverse slot 21, is a bolt 22 provided with a radial handle bar 23 extending outwardly throughout the open top of the slot and permitting the bolt to be shifted manually into one of the apertures 17 above the level of groove 15.

Notches 24 and 25 cut transversely into the side of slot 21 serve to retain the handle bar in place to prevent longitudinal shifting of the bolt into or out of aperture 17 as the case may be.

Similar bolt 26 provided with a handle bar 27, is slidably disposed in a slot 28 extending transversely in the body of the sliding member 18 below the level of groove 15. The bolt is adapted to be shifted into a selected aperture 17a below the level of tongue 20. Notches 29 and 30 permit the handle bar to be thrust into one of them, to prevent longitudinal movement of the bolt when it is desired to keep an end of the bolt in an aperture 17a or out of it as the case may be.

The sliding member 18 may be moved longitudinally within the open portion of member 10 to a desired position with respect to markings 32. To eliminate the possibility of having the sliding member drop out through the open space 13, I have provided a stop block 33, which is secured within the handle portion of the wrench so as to be in the path of said sliding member, when the latter is shifted in that direction. The block limits the extent of the movement of the sliding member so that fins 20 will not completely slide out of grooves 15. The block itself is retained in place by means of a screw 34, passing through said block into the end portion of the body 10 of the wrench.

I shall now describe the operation of my wrench:

Assuming that the wrench is to be applied to the head of a nut, such as is shown in dotted lines and identified by numeral 35 in Fig. 3, the wrench is first placed over the head of the nut in such a manner that one side of the head will bear against the inner surface 36 of the head portion of the wrench, whereupon the sliding member is moved manually against the opposite side of the head by way of a clamp. If the head

of the screw is of a standard size, one of the sliding bolts 22 or 26 will be opposite an aperture 17 or 17a, as the case may be, and the bolt may be shifted endwise into the respective aperture to lock the sliding member against displacement longitudinally with respect to the body of the wrench.

A provision has been made in my wrench to accommodate heads of nuts when a head has an uneven number of sides such as 3 or 5 or 7. In such a case, the sliding member would abut one side of the head, while the tip oppositely positioned at the juncture of two sides would fit into a V-shaped recess 37 in the head of the wrench as shown in Fig. 2. Normally the recess is filled by a plug 38 and retained in place by means of a screw 39 as shown in Fig. 3.

It will be understood that the wrench is not limited for use with conventional nuts but that it may be applied to nuts having heads oblong in shape, when two parallel sides may be considerably longer than the remaining sides. Having described the wrench, what I wish to claim is as follows:

1. A wrench comprising an oblong flat member of uniform thickness but tapering in one direction to form a broad head at one end and a narrow handle at the other end, the mid portion of the member along its longitudinal axis being open in the form of a slot of uniform width, one side wall of the slot being provided with a plurality of apertures spaced from each other and alined on one level, the other side wall being provided with a plurality of apertures spaced from each other and alined at a different level, a sliding member within the slot adapted to be moved longitudinally therein and having a flat face on the end looking towards the two sliding bolts seated transversely within the sliding member, one of the bolts being adapted to be shifted selectively into one of the apertures in one level, and the other bolt being adapted to be shifted selectively into one of said apertures at the other level, and handle means on each bolt to operate the same.

2. A wrench comprising an oblong body member of uniform thickness but tapering from one end which forms its head to the other end which forms a handle, the mid portion of the member along its longitudinal axis being open to form a slot of uniform width, one side wall of the slot being provided with a plurality of apertures spaced longitudinally at one level, and the other side wall of the slot being provided with a plurality of apertures spaced from each other at a lower level, calibration marks on the top surface of the body member indicating the location of each aperture, a sliding member within the slot adapted to be moved longitudinally therein and having a face at one end looking towards the head of the body member and adapted to serve as a clamp in opposition to the inner side of the head, two sliding bolts seated transversely in the sliding member, one at the level of apertures in one side wall of the slot, the other at the level of the apertures in the other side wall of the slot, and means to manually shift each bolt into one of the apertures at its level to prevent longitudinal movement of the sliding member with respect to the slot.

WALTER SNIEZYK.
